CLAIM

The ornamental design for a pedal boat, as shown and described.

DESCRIPTION

FIG. 1 is a perspective view of a pedal boat design showing my new design.

FIG. 2 is a front view of a pedal boat.

FIG. 3 is a rear view of a pedal boat.

FIG. 4 is a left side view of a pedal boat.

FIG. 5 is a right side view of a pedal boat.

FIG. 6 is a top view of a pedal boat.

FIG. 7 is a bottom view of a pedal boat.

FIG. 8 is an enlarged detail view of area 8 shown in FIG. 2; and,

FIG. 9 is an enlarged detail view of area 9 shown in FIG. 2. The broken lines illustrate the periphery of the enlarged views and portions of the pedal boat that form no part of the claimed design.
